HENRY A. OWEN, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

DRAFTING SYSTEM.

Application filed November 26, 1926. Serial No. 150,681.

The invention relates to drafting systems for cotton spinning and like machines, its object being to provide a simple roll combination which is as easy for the operator to 5 thread up and keep in order as the common three-roll system now in general use and which is capable of use throughout a wider range of draft ratios to produce yarn of better break test, and more particularly one 10 which permits the commercial use of drafts higher than 10. By this system, a single drafting of 22 or higher produces yarn of a break test as good or better than obtained by equivalent elongation produced in several 15 draftings. Heretofore such result has been obtained only at the expense of relatively complicated drafting apparatus involving the use of belts, friction plates and other contrivances likely to get out of order and difficult to keep in good working condition. The 20 characteristic of the present invention is that a level yarn is produced within the so-called high-draft range, or a stronger yarn at any lower draft, by the use of rolls alone without 25 need of belts or inter-roll guiding means of any kind, the roll organization being just as simple as that heretofore commonly used, practically as cheap to build in the first instance, and requiring no special skill or attention 30 to maintain in permanent service.

The drawing illustrates the preferred form of the invention, Fig. 1 being diagrammatic;

Fig. 2 a cross section of the rolls showing the weighting system; and

Fig. 3 a plan of Fig. 2.

The system comprises or includes a pair of front or delivery rolls 1 and 2, a group of intermediate rolls 3, 4 and 5, and a pair of back rolls 6 and 7. The four lower rolls 2, 40 4, 5 and 7 are journaled in roll stands 8 as usual and are all positively driven, being formed on continuous shafts extending the length of the machine as usual and driven at the rates explained below, by gearing at the end of the machine. This gearing is not illustrated because it can be readily supplied by any mechanic. The front top roll 1 and the back top roll 6 are held in superposition on 45 their respective lower rolls by the engagement of their gudgeons in the slots of the back bar arms 9, as usual. These arms and also the roll stands are shown of conventional design and are provided with usual adjustment facilities, including an extensible back bar fin-

ger 10. The top rolls 1 and 6 of the front 55 and back pairs are weighted by a saddle 11 and stirrup 12, or they might be self-weighted, the pressure in any event being sufficient to prevent any slipping of the roving and for the same purpose these rolls may be 60 leather covered. In the present case the weighting system includes an arm 11^a hinged to the back bar and arranged to bear on the rear top roll 6. The saddle 11 rests by its rear end in a groove in the weighting arm 11^a, 65 occupying different positions therein according to the adjusted distance between rolls 1 and 6. The stirrup 12 bears on the saddle 11 through its adjustment screw 12^a and always at the same point on the saddle for all ad- 70 justments, so that the manipulation of the screw 12^a has no effect except to shift the position of the stirrup relatively to the saddle and the distribution of the weight, to the rolls 1 and 6 is always substantially in the 75 same fixed ratio. The saddle 11 is high enough to permit the roll 3 to be easily removed from under it when desired. The bottom rolls 2 and 7 are fluted rolls, and the two pairs of rolls 1—2, and 6—7, may be 80 termed non-slipping rolls as distinguished from the intermediate group which is arranged to permit the roving to slip, relative- ly, through them.

The top intermediate roll 3 is supported 85 in and by the crotch of the two lower intermediate rolls 4 and 5 and driven by them, being free of all contact with the back bar arms 9, except such as may be necessary to guard against its endwise displacement. It 90 is thus free of frictional restraint or retardation, but it may have a clearer. The roving which may be single or double as desired, passes under the top roll and over the rolls 4 and 5, as indicated by dotted lines, and the path will be seen to be straight enough to be 95 self-threading, which is to say, that a broken end introduced straight into the back rolls will pass through the system coming out at the front rolls without requiring the lifting 100 of any rolls. For convenience of reference the portion of the yarn path between the back and intermediate rolls is designated *a*; that portion of it which lies between the nip lines of rolls 4 and 5 is designated *b* and that be- 105 tween the nip line of roll 4 and the front rolls, as *c*.

The top roll 33 is a gravity roll meaning

thereby that it is not weighted by stirrup or other applied weight. Its own weight is distributed on two lines of roving as indicated by Fig. 3, one passing under it near each end, 5 and it has two points of bearing on each, or four points of contact altogether. This is deemed important as thereby the roll 3 is rotated steadily and at the average speed of all the fibres passing beneath it, being helped 10 along by other points of contact whenever it would otherwise tend to lag at one of them. While it might be possible to use an applied weight on this roll, under conditions which would not involve objectionable interference 15 with its free rotation, such weighting is not desirable and is not in fact necessary. The weight of the roll itself can be sufficient for all purposes. For fine yarns of the order of 60s, it may properly weigh about 10 oz.; for 20 heavier yarns, such as 10s or heavier, it can be 12 oz., and ordinarily one weight of roll is satisfactory for all the yarn sizes which a given frame will ever be called upon to produce.

25 The intermediate bottom roll 4 is relatively small, about $\frac{1}{2}$ " in diameter, and is journaled close to the front rolls and with its top surface in a position slightly higher than the plane which is common to the nip lines 30 of front rolls 1 and 2 and intermediate rolls 3 and 5, and so that the roving portion c wraps around or bends over said roll for a portion of its circumference, approximating one-eighth of it or 45° of arc. Its proximity to 35 the front rolls is such that the roving distance c is slightly less than the average length of the staple. The relatively sharp curvature of the roving in the section c is also deemed important inasmuch as the forward ends of 40 some of the fibres emerging from the rolls 3-4 thereby have an opportunity to spring up clear of their companions and straighten out by their own inherent stiffness before and as they are drawn together into the nip of 45 the front rolls.

The intermediate lower roll 5 may be of the same or larger diameter than its companion roll 4 so long as it is so placed that it forms a crotch in which the top intermediate 50 roll 3 can be sustained without need of extraneous guidance. It is driven at the same surface speed as its companion roll. The distance b for which the yarn is in contact with the top intermediate roll 3 will be seen to be 55 slightly variable according to the diameters of the rolls of the group, but variation of this distance, within such limits, is apparently without effect on the product. In the case in hand, all the rolls, except roll 4, are of approximately the diameters standard in ring-spinning frames; to be specific, the diameter of rolls 1 and 6 is $\frac{15}{16}$ inch, of 5 and 7 is $\frac{7}{8}$ inch, 60 and of rolls 2 and 3 is 1 inch. The roving distance a is set slightly greater than the staple length, say from $1\frac{3}{8}$ to $1\frac{1}{2}$ inches.

The roving distance c is set, as above stated, so that it is always slightly less than the staple length; the roll 3 being set "on the staple" as it is termed. The adjustment of the distance c is ordinarily accomplished by 70 changing the position of the extension finger 10 which holds the top front roll 1, and so as to shift that roll backwards or forwards as conditions require, but for staple longer than $1\frac{1}{4}$ inch it is desirable to change also the distance between centers of the bottom rolls 2 and 4—5, as by the use of the adjustments 75 provided in the roll-stand base.

The intermediate rolls 3, 4 and 5 are slipping rolls, as above stated, which is to say, 80 that they are intended to permit the staple to be drawn through them, slipping through both nip lines. The lower rolls 4 and 5 may be and preferably are smooth or at least not sharply fluted, which would interfere with 85 slipping. The top roll 3 is smooth, cast iron or leather-covered, and preferably the former.

The draft ratio figured on the surface speed of the rolls is preferably 1.5 for the distance a or between 1 and 2.25, and anywhere from, say, 6 to 35 for the combined distances a , b and c , an over-all draft ratio of 22 being generally preferred for so-called "high-draft" spinning. The actual draft in distance a is or may be greater than the ratio of the roll speeds above given because the staple 90 pulls through the intermediate rolls under the draft of the higher speed non-slipping front rolls. 100

It is important that the top intermediate roll 3 be supported solely by the crotch of its two companion rolls, inasmuch as frictional retardation upon it, such as would occur if it had gudgeons rubbing against back bar slots, 105 is thus avoided and any retardation is found to interfere with the production of level yarn. Such top roll may however be provided with gudgeons if desired so long as the latter do not normally subject the roll to objectionable 110 retarding friction. The plane of the nip lines of the rolls 4 and 5 should thus be substantially horizontal so that the top roll will not be likely to become displaced in use and so that its weight will be about evenly distributed upon both rolls as above pointed out. 115

Within the principles above disclosed, it will be apparent that various modifications of the specific arrangement illustrated will produce equivalent results and without departing from this invention. 120

Claims:—

1. In a drafting roll system for roving, the combination of front and back pairs of rolls operating under pressure whereby they 125 are non-slipping in relation to the roving, and a group of intermediate rolls two of which are positively-driven rolls and a third of which rests in the crotch of the other two being driven by them, one of said positively- 130

- driven intermediate rolls being of relatively small diameter, as compared to said front and back rolls, and located close to said front rolls whereby its nip line is spaced less than the staple length from the nip line of said front rolls, the intermediate top roll being adapted to permit the roving to pull through beneath it under the draft exerted by said front rolls.
- 10 2. The combination of claim 1 wherein the said relatively small intermediate roll is so situated that approximately one-eighth or more of its circumference has contact with the roving passing to the front rolls.
- 15 3. The combination of claim 1 wherein the two lower intermediate rolls have their respective nip lines in a substantially horizontal plane thereby producing substantially equal pressure by the top roll at each nip line.
- 20 4. The combination of claim 1 wherein the intermediate top roll serves two lines of roving thereby having four points of contact whereby it is driven.
- 25 5. The combination of claim 1 in which the top front roll is adjustable around the circumference of the top lower roll in adjustment to different staple lengths.
- 30 6. The combination of claim 1 in which the speed ratio between the back and intermediate rolls approximates 1.5.

In testimony whereof, I have signed this specification.

HENRY A. OWEN.
